UNITED STATES PATENT OFFICE.

CHARLES DAVID BONSALE, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed August 2, 1926. Serial No. 126,455.

This invention relates to outside metal car roof wherein metal roof sheets are connected along their adjacent margins by ridge seam covers upon which said roof sheets slue or 5 oscillate so as to accommodate themselves automatically to the distortions of the car body.

The principal object of the present invention is a strong and durable seam construction that will secure a sluing or oscillatory movement of the sheets about points located near their adjacent margins. Other objects 10 are simplicity and cheapness of construction, compactness and economy of design and ease of assembly.

The invention consists principally of the improved seam construction hereinafter described; and it also consists in the combinations and arrangements of parts hereinafter 15 described and claimed.

In the accompanying drawing, which forms part of this specification and wherein like symbols refer to like parts wherever they occur,

Fig. 1 is a plan view of the ridge portion of an outside metal car roof provided with a ridge seam construction embodying my invention;

Fig. 2 is a vertical cross section through 30 said ridge seam on line 2—2 in Fig. 1; and

Fig. 3 is a bottom plan view of one of the ridge seam covers.

In the construction illustrated in the accompanying drawing, the metal roof sheets 35 4 rest on a wooden sheathing 5, which is supported at the ridge on a wooden ridge pole 6. The metal roof sheets 4 are arranged in two rows, one on each side of the ridge, the sheets on opposite sides of the ridge being spaced apart; and the sheets on the same side of the ridge are loosely positioned between wooden mullions or battens 7 arranged transversely of the car and secured at the roof sheathing.

The side and the ridge margins of the roof sheets 4 are provided with raised side and ridge marginal seam flanges or ribs 8 and 9, respectively. Side seam covers or caps 10 of substantially inverted channel-shaped section straddle the adjacent side seam flanges or ribs 8 of the roof sheets and the battens 7 located therebetween. The adjacent ridge seam flanges 9 of said sheets are connected by means of inverted channel-shaped ridge seam covers or caps 11 that

straddle said ridge seam flanges and have outstanding base flanges 12 that rest on the body portions of said sheets inside the side and ridge flanges thereof. The adjacent ends of the ridge seam covers 11 and side 60 seam covers 9 are held in position on the car by means of the usual four-way corner caps 13 that are secured in position by vertical bolts 14, which also secure the running board saddles (not shown) in position. 65

Secured to the under side of the top of each ridge seam cover 11 is a pivot piece or clip 15, whose cross-sectional shape comprises two longitudinally extending downwardly opening side marginal grooves or 70 channels 16 that are separated by an upwardly opening middle channel 17. The grooved pivot members or clips 15 are secured to the ridge seam cover, at points substantially midway of the length thereof, 75 preferably by rows of rivets 18 which extend through each of the channels 16 and thus prevent spreading thereof. The laterally spaced downwardly opening side marginal grooves or channels 16 of the pivot pieces or 80 clips 15 extend longitudinally of the ridge seam covers 11 and are adapted to straddle the middle portions of the spaced ridge seam flanges 9 of oppositely arranged roof sheets. 85

The channels 16 of the pivot members are made wider at their ends than at their middle, preferably by reversely curving or bowing the side walls of said channels from their middle towards their ends. The width of the narrow middle portion of the downwardly 90 opening grooves 16 corresponds to the width of the ridge seam flanges 9 of the sheets, whereby said grooves snugly embrace said flanges and thus prevent relative or joint bodily movement of said sheets crosswise of the car. By reason of the widening of the downwardly opening channels 16 from their middle towards each end, said grooves are normally in contact with the ridge seam flanges 9 of the sheets for only a slight distance at the middle of the ridge end of said sheet, with the result that the roof sheets are forced to oscillate or rock upon the narrow middle portions of said channels in 95 accommodating themselves to the rocking and weaving of the car frame in service.

One of the principal advantages of the foregoing construction is that it permits the pivot pieces or clips to be replaced when they become worn or damaged in service. 110

Another advantage is that said clips serve to reinforce and stiffen the ridge seam covers against forces tending to distort said seam covers or clips and thus interfere with the sluing movement of the roof sheets.

5 My invention is not restricted to the precise forms and arrangements shown and described.

What I claim is:

- 10 1. A flexible car roof comprising roof sheets spaced apart along their adjacent margins and having raised ribs extending along said margins, a seam cover straddling the ribs of the adjacent sheets, and a member secured to said seam cover and straddling each of said ribs.
- 15 2. A flexible car roof comprising roof sheets spaced apart along their adjacent margins and having raised ribs extending along said margins, a seam cover straddling the ribs of adjacent sheets, and a member rigidly secured to said seam cover and having contact with both sides of each of said ribs for a portion of their length only.
- 20 3. A flexible car roof comprising roof sheets spaced apart along their adjacent margins and having raised ribs extending along said margins, a seam cover straddling the ribs of adjacent sheets, and a pivot member secured to said seam cover and having downwardly opening grooves formed therein adapted to straddle the ribs of adjacent sheets, said grooves being wider at the ends than at the middle.
- 25 4. A flexible car roof comprising roof sheets spaced apart along their adjacent margins and having raised ribs extending along said margins, a seam cover straddling the ribs of adjacent sheets, and a pivot clip secured to the under side of the top of said

seam cover and being provided with downwardly opening grooves which straddle the ribs of adjacent sheets and engage both sides of each of said ribs for a portion of their length only.

5 A flexible car roof comprising roof sheets spaced apart along their adjacent margins and having raised ribs extending along said margins, a seam cover straddling the ribs of adjacent sheets, and a pivot clip located beneath said seam cover and having downwardly opening grooves that straddle the ribs of adjacent sheets and engage both sides of each of said ribs for a portion of their length only, said clip being rigidly secured to said seam cover by fastening members located adjacent to each of said grooves.

6. A seam cover for a car roof, said seam cover being of substantially inverted channel-shaped section, and a clip secured to said seam cover and having laterally spaced downwardly opening grooves extending longitudinally thereof.

7. A seam cover for a car roof, said seam cover being of substantially inverted channel-shaped section, and a clip secured to said seam cover and having laterally spaced downwardly opening grooves extending longitudinally thereof that are of greater width at the ends than at the middle.

8. A seam cover for a car roof, said seam cover being of substantially inverted channel-shaped section, and a pivot clip secured to the under side of the top of said seam cover and having downwardly opening grooves therein that are of greater width at the ends than at the middle.

Signed at New Kensington, Pa., this 26th day of July, 1926.

CHARLES DAVID BONSALL.
